US00D829235S

(12) **United States Design Patent** (10) Patent No.: **US D829,235 S**
Gangcuangco et al. (45) Date of Patent: **** Sep. 25, 2018**

(54) **ELECTROPHORESIS AND IMAGING SYSTEM DISPLAY SCREEN WITH GRAPHICAL USER INTERFACE**

(71) Applicants: **Life Technologies Corporation**, Carlsbad, CA (US); **Life Technologies Holdings PTE Limited**, Singapore (SG)

(72) Inventors: **Jefferson Gangcuangco**, Singapore (SG); **Sean Zimmerman**, San Diego, CA (US); **Joshua Mead**, San Diego, CA (US); **Scott Rickes**, San Diego, CA (US)

(73) Assignees: **LIFE TECHNOLOGIES CORPORATION**, Carlsbad, CA (US); **LIFE TECHNOLOGIES HOLDINGS PTE LIMITED**, Singapore (SG)

(**) Term: **15 Years**

(21) Appl. No.: **29/606,325**

(22) Filed: **Jun. 2, 2017**

(51) LOC (11) Cl. **14-04**

Primary Examiner — Kevin K. Rudzinski

Assistant Examiner — Jack Reickel

(57) **CLAIM**

The ornamental design for an electrophoresis and imaging system display screen with graphical user interface, as shown and described.

DESCRIPTION

FIG. 1 is a view of a first embodiment of an electrophoresis and imaging system display screen with graphical user interface of our new design; and,

FIG. 2 is a view of a second embodiment of an electrophoresis and imaging system display screen with graphical user interface of our new design.

The broken line showing of a display screen and portions of the graphical user interface is included for the purpose of illustrating portions of the article and forms no part of the claimed design.

1 Claim, 2 Drawing Sheets
